UNITED STATES PATENT OFFICE

CHARLES E. WAREAM, OF NORWOOD, OHIO, ASSIGNOR TO THE AMERICAN LAUNDRY MACHINERY COMPANY, OF CINCINNATI, OHIO, A CORPORATION OF OHIO

NECKBAND CLAMP

Application filed December 14, 1922, Serial No. 608,838. Renewed June 11, 1928.

This invention relates to improvements in shirt ironing machines and more particularly, to a neckband clamp therefor.

The object of the invention is to provide an improved neckband clamp which securely holds the neckband of a shirt to the neckband block of the bed or lower pressing member, thereby enabling the shirt to be held on the bed in proper alignment for the ironing operation.

A further object of the invention is to provide an improved neckband clamp having a single operating handle for raising and lowering the neckband clamping member with respect to the bed and for horizontally moving said member along the same into and out of clamping engagement with the neckband block, said operating handle being conveniently arranged and readily manipulated.

Further objects of the invention are in part obvious and in part will appear more in detail hereinafter.

In the drawings, which represent one suitable embodiment of the invention, Fig. 1 is a front elevation of a shirt ironing machine embodying my invention; Fig. 2 is an end view thereof with the upper pressing member raised and the neckband clamping member in operative or clamping position; Fig. 3 is a plan view of the bed or lower pressing member, with the neckband clamping member in raised position; Fig. 4 is a front elevation thereof; and Figs. 5, 6 and 7 are detail views, respectively showing the neckband clamping member in raised, released and clamping position.

Referring to the drawings, the shirt ironing machine therein shown for the purpose of illustrating the present invention, comprises a suitable frame 1 having a pedestal or standard 2 for supporting the padded bed, or lower pressing member 3, upon which the shirt is ironed. Said bed is provided at one end thereof with a neckband block 4 suitably secured thereto and to which block the shirt neckband is clamped during the ironing operation. Pivotedly mounted in the frame at the rear of said bed is a swinging lever 5 provided at its front end with a head or upper pressing member 6, which is adapted to be

brought down by suitable treadle mechanism 7 into engagement with the bed for the ironing operation. Said upper pressing member 6 is provided at one end thereof with a suitable cut-out portion 8 to accommodate the neck-band block 4 of the lower pressing member.

In the present construction, the shirt ironing machine is provided with suitable yoke clamps, indicated generally at 9, which hold the yoke portions of the shirt to one end of the bed and thereby assist in holding the shirt in proper alignment for the ironing operation. While said yoke clamps may be of any suitable construction, the ones here shown each comprise a lever arm 10 having its lower end pivotally mounted in an upwardly extending bracket 11 suitably supported upon the outer end of a horizontally extending bracket 12, which bracket in turn is suitably secured to the pedestal or standard 2 of the frame. Said lever arms 10 are provided at their upper ends with suitable pads 13 for engaging the yoke portions of the shirt, and are adapted to be moved into and out of clamping engagement by rods 14 swivelly connected therewith, the other ends of said rods being connected by links 15 to a shaft 16, to which is secured an operating handle 17.

Referring now to my improved neckband clamp, said clamp comprises a lever arm 18 pivoted intermediate its ends, as at 19, in the upper end of bracket 11, the lower end of said arm being suitably connected to one end of an eye bolt 20, swivelled at 21 in bracket 11 and provided at its other end with a suitable tension spring 22, for normally holding said lever arm in an upright, yielding position, as indicated in the drawings.

The upper bifurcated end of lever arm 18 is provided with an eccentric 23 fast upon a stud 24, to one end of which is secured an operating handle 25 for turning said eccentric, rotary movement of said handle being limited by a stop lug 26 thereon which is adapted to engage a pin 27 on the outer face of one of the bifurcated end portions, as clearly shown in Fig. 5. Journalled on said eccentric is a yoke member 28 having its front free ends connected to a strap or bail member 29 adapt-

ed for co-operation with the neckband block 4 in holding the shirt neckband to the neckband block during the ironing operation. Said neckband block is provided near its upper end with suitable lugs 30 which prevent said bail member from rising when in clamping position.

Rotation of operating handle 25 moves the strap or bail member 29, by action of eccentric 23, back and forth along the bed or lower pressing member, into and out of clamping engagement with the neckband block 4. In order to raise said bail member from the bed and permit a shirt to be placed upon the bed, yoke member 28 is provided in its rear end portion with a substantially semi-circular slot 31, in which travels the projecting end portion of a pin 32 suitably secured in eccentric 23. By means of this pin and slot connection, bail member 29 may be raised and lowered with respect to the bed by operation of handle 25, as will more fully appear from the operation of the mechanism, now to be described.

Let us assume that the strap or bail member 29 is in raised position, as indicated in Fig. 5, in which position it is held by the operating handle 25 which acts as a counter-weight, further downward counter-clockwise movement of said handle being prevented by engagement of lug 26 and pin 27. By turning handle 25 in a clockwise direction, and thereby releasing its effect as a counter-weight, bail member 29 will be free to fall onto bed 3 or a shirt thereon, yoke member 28 and eccentric 23 moving substantially as a unit, the lower end 31^a of yoke slot 31 remaining in engagement with eccentric pin 32 during such downward movement. When the bail member 29 strikes the bed or a shirt thereon, it will be in released or extended position, as shown in Fig. 6, and when this point is reached, further rotation of handle 25 will cause pin 32 of the eccentric to leave the lower end 31^a of slot 31 and travel toward the other end 31^b thereof. During the time pin 32 is travelling from the lower end 31^a of slot 31 to the upper end 31^b thereof, bail member 29 will be moving from released or extended position toward neckband block 4 and exerting a clamping action upon the shirt neckband therearound, which clamping action will be continued until pin 32 strikes the upper end 31^b of slot 31, at which point the shirt neckband will be securely clamped to the neckband block.

To release the clamping strap or bail member 29, operating handle 25 is moved in a counter-clockwise direction. During the time pin 32 is travelling from the upper end 31^b of yoke slot 31 to the lower end 31^a thereof, said bail member will be moving outwardly to released or extended position, by the action of eccentric 23. Further counter-clockwise rotation of said handle will cause pin

32 to engage the lower end 31^a of the slot and raise the bail member 29 to the elevated position shown in Fig. 5, ready for the next ironing operation.

All of the movements of the neckband clamping member are produced by a single operating handle relative to a single line or axis. The mechanism is therefore exceedingly simple in construction and readily manipulated.

What I claim is:—

1. Neck-band clamping mechanism, comprising an eccentric, clamping means journaled thereon and adapted for cooperation with a neck-band block, operating means for said eccentric whereby said clamping means may be horizontally moved into and out of clamping engagement with said neck-band block, and an interlocking connection between said eccentric and said clamping means whereby continued operation of said operating means will raise or lower said clamping means relative to said neck-band block.

2. Neck-band clamping mechanism, comprising an eccentric, clamping means journaled thereon and adapted for cooperation with a neck-band block, operating means for said eccentric whereby said clamping means may be horizontally moved into and out of clamping engagement with said neck-band block, and a lost motion interlocking connection between said eccentric and said clamping means whereby continued operation of said operating means will raise or lower said clamping means relative to said neck-band block.

3. Neck-band clamping mechanism, comprising an eccentric, clamping means journaled thereon and adapted for cooperation with a neck-band block, operating means for said eccentric whereby said clamping means may be horizontally moved into and out of clamping engagement with said neck-band block, and a slot and pin connection between said eccentric and said clamping means whereby continued operation of said operating means will raise or lower said clamping means relative to said neck-band block.

4. Neck-band clamping mechanism, comprising an eccentric, clamping means journaled thereon and adapted for cooperation with a neck-band block, operating means for said eccentric whereby said clamping means may be moved into and out of clamping engagement with said neck-band block, an interlocking connection between said eccentric and said clamping means whereby continued operation of said operating means will raise or lower said clamping means relative to said neck-band block, and means for limiting the upward movement of said clamping means.

5. Neckband clamping mechanism, comprising an eccentric, clamping means journaled thereon and adapted for co-operation

with a neckband block, an operating handle for said eccentric whereby said clamping means may be horizontally moved into and out of clamping engagement with said neckband block, a pin and slot connection between said eccentric and clamping means whereby continued movement of said operating handle will move said clamping means upwardly with respect to said neckband block, and means for limiting the movement of said operating handle whereby said clamping means will be held in raised position by the weight of said operating handle.

6. In combination, a neckband block and neckband clamping mechanism, said mechanism including a movable support with clamping means movable thereon between full release and full clamping locked positions, yieldable means associated with said support and tending therethrough to move said clamping means against said block when the clamping means is in clamping position whereby various work thickness will be accommodated between said block and clamping means, and operator-operated means movable between full release and full clamping locked positions for controlling said movement of said clamping means on said support.

30 In testimony whereof I hereby affix my signature.

CHARLES E. WAREAM.
